CLAIM

The ornamental design for a physical exerciser for mounting on bed, as shown and described.

DESCRIPTION

FIG. 1 is a front elevational view of a physical exerciser for mounting on bed showing my new design, the side opposite being substantially a mirror image; FIG. 2 is an end elevational view thereof; and FIG. 3 is a bottom plan view thereof.

The shading shown partially in fragment on the flap members represents an overall texture on said members.
